CLAIM

The ornamental design for landscape edging, as shown and described.

DESCRIPTION

FIG. 1 is a perspective view of a landscape edging showing my new design;

FIG. 2 is a top plan view thereof;

FIG. 3 is a front elevational view thereof;

FIG. 4 is a bottom plan view thereof;

FIG. 5 is a rear elevational view thereof; and,

FIG. 6 is a left side elevational view thereof, the opposite side of which is a mirror image.
The broken lines in the drawings represent portions of the landscape edging that form no part of the claimed design.**1 Claim, 2 Drawing Sheets**(56)
